CLAIM

The ornamental design for a Bluetooth speaker, as shown and described.

DESCRIPTION

FIG. 1 is a perspective view of a Bluetooth speaker showing my new design;

FIG. 2 is a bottom perspective view thereof;

FIG. 3 is a front elevational view thereof, the rear side being a mirror image;

FIG. 4 is a left side elevational view thereof, the right side being a mirror image;

FIG. 5 is a top plan view thereof; and,

FIG. 6 is a bottom plan view thereof.

The broken lines showing of FIGS. 2, 3, 4, and 6 are for the purpose of illustrating portion of the Bluetooth speaker that forms no part of the claimed design.

1 Claim, 6 Drawing Sheets(56)
